DESIGN FOR A ROULETTE DEVICE

Arthur Popper, New York, N. Y.

Application June 29, 1936, Serial No. 63,561

Term of patent 7 years

To all whom it may concern:

Be it known that I, Arthur Popper, a citizen of the United States, residing at New York city, in the county of New York and State of New York, have invented a new, original, and ornamental Design for a Roulette Device, of which the following is a specification, reference being had to the accompanying drawing, forming a part thereof:

Fig. 1 is a perspective view of the roulette device with the lid partly open, showing my new design.

Fig. 2 is a plan view of the same.

Fig. 3 is a perspective view of the same with the lid fully closed.

I claim:

The ornamental design for a roulette device, as shown and described.

ARTHUR POPPER.
